UNITED STATES PATENT OFFICE.

JOHN E. PARKER, OF BELOIT, WISCONSIN.

DRIVE-WELL POINT.

SPECIFICATION forming part of Letters Patent No. 313,882, dated March 17, 1885.

Application filed November 12, 1884. (No model.)

To all whom it may concern:

Be it known that I, JOHN E. PARKER, of Beloit, in the county of Rock and State of Wisconsin, have invented certain new and useful 5 Improvements in Drive-Well Points; and I do hereby declare the following to be a full, clear, and exact description of the invention, such as will enable others skilled in the art to which it pertains to make and use it, reference being had to the accompanying drawings, which form a part of this specification.

My invention relates to improvements in drive-well points; and its objects are, first, to furnish a drive-well point consisting of one entire piece; second, to provide a drive-well point so constructed that when in position water may have free access to the interior thereof through lateral orifices. I consider malleable iron the most suitable material out 15 of which to manufacture the herein-described drive-well point.

Referring to the drawings, Figure 1 represents a view of one of my improved drive-well points before being covered with the customary wrappings of wire-cloth and perforated plate. Fig. 2 represents a longitudinal central vertical section of Fig. 1, through the dotted line $x-x$ of Fig. 3. Fig. 3 represents a transverse sections of Fig. 1, through the dotted line $y-y$.

The acorn-shaped point A will be sufficiently strong if cast hollow, as shown at A'. The point is enlarged at A², in order that in descending into the earth it may make a hole of 35 larger diameter than that of the shaft-like

portion B, thereby usually saving the wrappings of the point from skinning by coming in contact with stones projecting from the sides of the hole. The columnar portion of the point consists exteriorly of a series of alternating annular projections, C, and transverse grooves D, interiorly of the longitudinal grooves and strengthening-ribs E F.

G are rectangular openings extending from the exterior to the interior of the point 40 through the grooves D. The annular projections C furnish supports for the wrappings of wire-cloth and perforated plate, while the transverse grooves D afford free passage-ways for water flowing through the openings G into 45 the reservoir H. The interior of the upper end, I, of the point is furnished with an internal screw, into which can be turned an external screw cut on the end of a water-pipe.

Having fully described my invention, what 50 I claim as new, and desire to secure by Letters Patent, is—

As a new article of manufacture, the herein-described drive-well point having the acorn-shaped point A, enlarged at A², the exterior 55 annular projections, C, intermediate transverse grooves, D, the latter provided with the openings G, the longitudinal grooves E, and longitudinal strengthening-ribs F, substantially as described.

JOHN E. PARKER.
